UNITED STATES PATENT OFFICE.

JOSEPH SOSS, OF BROOKLYN, NEW YORK.

DOOR LATCH.

Application filed May 14, 1926. Serial No. 108,047.

This invention relates to door latches and particularly to devices of this class for use in connection with the doors of motor vehicles; and the object of the invention is to provide a door latch with means cooperating with the bolt of a lock mounted in a door to provide an anti-frictional engagement of the bolt with said means and further to compensate for any movement of the bolt with reference to the latch in any direction; a further object being to provide a latch device with one or more steel balls in connection with which the bolt of a lock is adapted to operate when the door is in closed position; a still further object being to provide in combination with a latch device employing an anti-frictional member, a latch bolt having two beveled sides, the bevel on one side being slight with reference to the longitudinal plane of the bolt and said side cooperating with the anti-frictional member of the latch in such manner as to retain the latch bolt in connection with said anti-frictional member under tension at all times; and further in the provision of a straight face on said side of the bolt arranged in parallel relation with the longitudinal plane of the bolt; a still further object being to provide a latch device employing at the outer end thereof a raised beveled portion over which the inner beveled side of the bolt is adapted to pass, said raised portion forming an auxiliary latch stop, and inwardly of said raised portion, the latch device is provided with an anti-frictional device engaging the straight or slightly beveled side face of the bolt to retain the door in closed position and under tension; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a face view of a door frame showing one form of latch device mounted in connection therewith.

Fig. 2 is a partial section on the line 2—2 of Fig. 1 and illustrating a part of the door and the bolt thereof in closed position, and in dotted lines, in a partially closed position. 55

Fig. 2^a is a detail view similar to Fig. 2 but showing a modification.

Fig. 3 is an inside view of the latch device shown in Figs. 1 and 2.

Fig. 4 is a view similar to Fig. 1 but showing a modification. 60

Fig. 5 is a section on the line 5—5 of Fig. 4.

Fig. 6 is a view similar to Fig. 1 but showing a slight modification.

Fig. 7 is an end view of the device shown 65 in Fig. 6.

Fig. 8 is a view similar to Fig. 2 but showing another modification.

Fig. 9 is a section on the line 9—9 of Fig. 8; and, 70

Fig. 10 is a view similar to Fig. 9 but showing another modification.

In the drawing, I have indicated at 11 the framework of a door in connection with which the latch device 12 is mounted as seen in Fig. 75 2 of the drawing. At 13, I have indicated a part of the door having a latch bolt 14, which in the construction shown in Fig. 2 of the drawing, is provided with a beveled inner face 15 and a slightly beveled outer face 16, 80 while in Fig. 2^a of the drawing, I have shown a modified form of bolt 14^a having a beveled inner face 15^a and a slightly beveled outer face 16^a which terminates in the outer end of the bolt in a comparatively straight face 16^b 85 arranged in parallel relation with reference to the longitudinal plane of the bolt or movement of the bolt.

The latch device 12, in the construction shown in Figs. 1 to 3 inclusive, is preferably fashioned from sheet metal to form at the outer end thereof a raised beveled face 17 having a screw aperture 18 adjacent its outer end for receiving an attaching screw 19. The inner end of the raised portion 17 terminates 95 in a stop shoulder 20 forming an auxiliary stop for the bolt 14 to retain the door 13 in a partially closed position. Inwardly of the stop 20, the device is fashioned to form a pair of oppositely arranged ears 21 by curling the 100 metal from which the stop device 12 is formed, and so fashioned to provide between

the ears 21, a seat for a steel ball 22, the periphery of which projects beyond the inner faces 23 of the ears 21 as clearly seen in Figs. 1 and 2 of the drawing, whereby the outer 5 bevel face 16 of the bolt 14 is adapted to engage said ball to lock the door 13 in its closed position. It will be understood that the bolt 14 is of the usual spring pressed type normally projected by the action of the 10 spring and the beveled face 16 is such as to provide a tensional engagement of the bolt 14 with the ball 22 at all times, the bevel face compensating for any wear that may prevail in the extended use of the door, the bevel face 15 16 being at such an angle as to prevent the opening of the door until the bolt 14 has been retracted by the knob or handle usually employed for this purpose. With the structure shown in Fig. 2^a, it will be apparent that the 20 bevel face 16^a will compensate for the wear on the bolt and in the initial position of the parts, the bolt 14 or 14^a is held inwardly of its normal extreme outward movement by the bevel faces 16 and 16^a.

25 The space formed between the ball 22 and the stop shoulder 20 is adapted to receive the bolt 14, and the latch device within this space is provided with a screw aperture 24 for receiving a screw 25 to aid in securing the device to the door frame 11 as will be apparent. It will also be noted on a consideration of Fig. 2 of the drawing, that the bottom portion of the latch plate is fashioned to form a seat for the ball 22, as seen at 26.

30 With the construction shown in Figs. 6 and 7 of the drawing, the attaching device is of the same general contour as the device shown in Figs. 1 to 3 inclusive except that the device is made from a solid piece of metal by molding, die-casting or forging, or in any other 35 desired manner. With this construction, the ears 21 are joined and reinforced by the formation of the arc-shaped recesses 27 in the opposite sides thereof, one of which recesses 40 is seen in Fig. 7 of the drawing. In Figs. 4 and 5 of the drawing, I have shown another modification of the construction shown in Figs. 1 to 3 and 6 and 7 wherein two balls 22^a are supported in a comparatively wide latch 45 plate instead of one ball as shown in said other figures. In this construction, the ears 21 are more widely spaced apart by the greater width of the body of the device 12 and interposed between said ears is a spacing 50 member 28 secured to the latch plate by riveting or in any other manner as seen at 29, and the opposite faces of the member 28 are provided with arc-shaped recesses 30 to receive the balls 22^a. It will be understood 55 that the structure shown in Figs. 4 and 5 is intended for use in connection with comparatively wide latch bolts such as the bolts 14 and 14^a. In Figs. 8 and 9 of the drawing, I have shown another modification wherein 60 a latch device 31 is fashioned from a solid

body of metal as in the formation of the latch devices shown in Figs. 4, 5, 6 and 7, the outer end portion being fashioned to form a raised beveled face 32 similar to the bevel face 17, and which terminates at its inner end in a stop shoulder 33 similar to the shoulder 20. In spaced relation to the shoulder 33, the device 31 is provided with a raised body 34 at its inner end within which is permanently retained a roller 35 which is rotatable within the body 34, and which projects beyond the inner end of said body 34 as will be apparent and as seen in Fig. 8 of the drawing. The projecting portion of the roller 35 is adapted to engage the bolt of the like in the manner of the engagement of the bolt 14 with the ball 22 as seen in Fig. 2 of the drawing. It will be understood that the roller 35 is retained against displacement from the body 34 by the seat 36 in said body, in which seat, the roller 40 rotates.

In Fig. 10 of the drawing, I have shown another modification wherein the inner end portion of a latch plate 37 is provided with spaced ears 38 in which are mounted screws 39 having conical adjacent ends adapted to enter similar recesses 40 in the opposite ends of a roller 41 mounted within and between said ears 38. It will be understood that the screws 39 serve to retain the roller 40 in 45 position and also permits of the rotation of said roller on said screws. From the foregoing it will be apparent that when the balls are employed, the latch bolt in its several movements thereof caused by vibration or 50 the like and when the door is in closed position, may operate upon the bearing balls universally to eliminate friction noises of any kind or class that might otherwise prevail when the latch bolt would slidably engage a stationary body on a latch bolt. With the rollers employed, movement of the latch bolt longitudinally of the bolt action will 55 operate to prevent noises and reduce friction between said parts in such operation.

60 It will be understood that my invention is not necessarily limited to the specific structural details herein shown and described, nor the specific contour of the latch device or the manner of its making, nor am I necessarily limited to the specific form of latch bolts herein shown and described, and various changes in and modifications of the construction herein set out may be made within the scope of the appended claims without departing from the spirit of my invention or sacrificing its advantages.

65 It will be noted upon a consideration of Figs. 2 and 3 of the drawing that the latch or lock bolt 14—14^a extends beyond the axis 125 of the ball 22 with relation to a line extending at right angles to the longitudinal plane of the bolt and passing through said axis, and this will also be true in the use of the several devices employed to effect the locking of the 130

door or retaining the same against accidental displacement. It will also be noted that in the outward movement of the bolt 14 by its usual spring, and the engagement of the 5 beveled face 16 with the ball 22 or the other anti-frictional device employed, a wedge-like action is produced between the two movable bodies to firmly wedge and lock the bolt in position and to retain the same in such position 10 under tension.

Having fully described my invention, what I claim as new and desire to secure by Letters Patent, is:—

1. A latch device comprising a body 15 adapted to be secured to a door frame, a ball mounted in fixed position in said body and rotatable in its support and against which the outer side face of the latch bolt of a door is adapted to rest when the door is in a closed 20 position in said door frame, and said latch device being provided outwardly of said ball with a beveled striking face having a stop shoulder in connection with which the latch bolt is adapted to operate to form an auxiliary door catch for retaining the door in a 25 partially closed position.

2. A latch of the class described comprising a body, one end of which is fashioned to form a beveled striking face terminating at 30 its inner end in a stop shoulder, means at the other or inner end of the device for supporting an anti-frictional member therein which projects beyond the inner face of the device and in connection with the projecting 35 end of which a latch bolt of a door is adapted to operate in retaining the door in closed position.

3. A latch of the class described comprising a body, one end of which is fashioned 40 to form a beveled striking face terminating at its inner end in a stop shoulder, means at the other or inner end of the device for supporting an anti-frictional member therein which projects beyond the inner face of the 45 device and in connection with the projecting end of which a latch bolt of a door is adapted to operate in retaining the door in closed position, and means for securing said latch device to the frame of a door.

4. A latch of the class described comprising a body, one end of which is fashioned to form a beveled striking face terminating at 50 its inner end in a stop shoulder, means at the other or inner end of the device for supporting an anti-frictional member therein which projects beyond the inner face of the 55 device and in connection with the projecting end of which a latch bolt of a door is adapted to operate in retaining the door in closed position, means for securing said latch 60 device to the frame of a door, and said anti-frictional device comprising a steel ball whereby relative movement of the latch bolt may be compensated for by the rotary movement of said ball.

5. The combination with a door and a spring actuated bolt carried thereby, said bolt having its inner face beveled and its opposite or outer face slightly beveled, of a latch device adapted to be secured to the 70 door frame and provided at its inner end with projecting anti-frictional means in connection with which the outer face of the bolt is adapted to operate for retaining the door in closed position. 75

6. The combination with a door and a spring actuated bolt carried thereby, said bolt having its inner face beveled and its opposite or outer face slightly beveled, of a latch device adapted to be secured to the 80 door frame and provided at its inner end with projecting anti-frictional means in connection with which the outer face of the bolt is adapted to operate for retaining the door in closed position, and means on said 85 latch device outwardly of said anti-frictional means for forming an auxiliary stop.

7. The combination with a door and a spring actuated bolt carried thereby, said bolt having its inner face beveled and its 90 opposite or outer face slightly beveled, of a latch device adapted to be secured to the door frame and provided at its inner end with projecting anti-frictional means in connection with which the outer face of the bolt 95 is adapted to operate for retaining the door in closed position, and means on said latch device outwardly of said anti-frictional means for forming an auxiliary stop, said last named means involving a beveled face 100 over which the bolt is adapted to pass prior to its engagement with said anti-frictional device.

8. The combination with the spring actuated bolt of a door lock, said bolt having 105 a slightly beveled outer face, of a latch device provided with anti-frictional means adapted to be engaged by said beveled face of the bolt to firmly secure and retain the bolt in position when the door is closed, and 110 said latch device having an auxiliary stop outwardly of said frictional device adapted to be engaged by said bolt to retain the door in a partially closed position.

9. A door latch of the class described, the 115 inner end portion of which, when mounted in the door frame and with reference to the swinging movement of the door is provided with a fixedly supported and rotatable anti-frictional device which projects beyond the 120 inner end of said latch whereby in the engagement of the latch bolt therewith when the door is closed, said bolt is free to engage the projecting portion of said anti-frictional device only. 125

10. A door latch of the class described, the inner end portion of which, when mounted in the door frame and with reference to the swinging movement of the door is provided with an anti-frictional device which 130

projects beyond the inner end of said latch whereby in the engagement of the latch bolt therewith, said bolt is free to engage the projecting portion of said anti-frictional device only, and the outer end portion of the latch being provided with an inwardly beveled surface, terminating in a supplemental

stop shoulder arranged on said latch outwardly of said anti-frictional device.

In testimony that I claim the foregoing as my invention I have signed my name this 7th day of May 1926.

JOSEPH SOSS.
